UNITED STATES PATENT OFFICE.

CARL E. BEILHARZ, OF JOLIET, ILLINOIS, ASSIGNOR TO WM. E. PRATT MFG. COMPANY, OF CHICAGO, ILLINOIS.

MOUSETRAP.

1,414,066.

Specification of Letters Patent. Patented Apr. 25, 1922.

Application filed May 27, 1921. Serial No. 473,186.

To all whom it may concern:

Be it known that I, CARL EUGENE BEILHARZ, a citizen of the United States of America, residing at Joliet, in the county of Will and State of Illinois, have invented certain new and useful Improvements in Mousetraps, of which the following is a specification.

This invention relates to traps and has special reference to a trap for mice, rats and the like of the type wherein a spring actuated yoke is used to catch the mouse.

One important object of the invention is to provide a novel arrangement for holding the various parts of the device on the base.

A second important object of the invention is to provide an improved form of trap wherein the usual nails or tacks employed for holding the moving parts may be eliminated.

With the above and other objects in view, the invention consists in general of certain novel details of construction and combinations of parts hereinafter fully described, illustrated in the accompanying drawings, and specifically claimed.

In the accompanying drawings, like characters of reference indicate like parts in the several views, and:—

Figure 1 is a plan view of the improved trap.

Figure 2 is a side elevation thereof.

Figure 3 is a section on the line 3—3 of Figure 1 with the working parts removed.

Figure 4 is a perspective view of the improved means for holding the parts on the base.

Figure 5 is a perspective view of the modified form of treadle.

In carrying out the objects of the invention there is provided a base 10. Extending across this base 10 is a strip of metal consisting of a body portion 11 which is cut and bent upward to provide a pair of spaced ears 12 between which is mounted the treadle or trigger 13. The strip 11 is also punched out adjacent each end and turned upward to form ears 14. A pivot member or pin 15 extends between ears 14 and on this is mounted a yoke 16 which is normally urged to the position shown in full lines in Figure 2 by means of a coil spring 17 one

end of which is engaged over the yoke as at 18 while the other end rests on the base 10 as at 19. The strip 11 is of such length that the parts beyond the ears 14 may be bent down as at 20 to lie alongside of the sides of the base 10 while the extremities are bent under the base as at 21 and may, if desired, be provided with prongs 22 which are forced into the base when the device is assembled. With this arrangement of the strip 11 no tacks, nails, or other fastenings are needed to retain the strip in position on the base and thus the danger of the strip being detached by the pulling out of nails or tacks is eliminated.

Pivoted to an eye 24 is a keeper 25 which, when the trap is set, extends over the yoke 16 as shown in the dotted line position in Figure 2 and has its end engaged between trigger 13 thus holding the trap set until the treadle part of the trigger 13 is depressed whereupon the yoke will fly over and catch the animal which has depressed the trigger.

In the modified form of treadle shown in Figure 5 it will be seen that the treadle consists of a wooden body 18' with a metallic grip and pivot 18''.

There has thus been provided a simple and efficient device of the kind described and for the purpose specified.

It is obvious that minor changes may be made in the form and construction of the invention without departing from the material principles thereof. It is not therefore desired to confine the invention to the exact form herein shown and described, but it is wished to include all such as properly come within the scope claimed.

Having thus described the invention, what is claimed as new, is:—

In a trap of the class described a base, and a bearing member for pivotally attaching working parts of the trap to said base and comprising a single strip of material having upstanding portions forming bearing ears and having its ends bent down around the sides of the base and extending therebeneath, said bearing member further having prongs on its extremities entering said base.

In testimony whereof I affix my signature.
CARL E. BEILHARZ.
